DAVID J. SEAMAN, OF SOUTH BEND, INDIANA.

DESIGN FOR A FONT OF TYPE.

SPECIFICATION forming part of Design No. 34,385, dated April 16, 1901.

Application filed March 22, 1901. Serial No. 52,444. Term of patent 14 years.

To all whom it may concern.

Be it known that I, DAVID J. SEAMAN, a citizen of the United States of America, residing at South Bend, in the county of St. Joseph and State of Indiana, have invented and produced a new and original Design for a Font of Type, of which the following is a specification, reference being had to the accompanying drawing, forming a part hereof.

10 In the just - mentioned drawing I have shown a plan view of my design.

The leading feature of the design is the representation of stems forming the letters and bearing berries, with leaves springing from the stems above and below the letters. The stems or twigs are shown following the general lines of the letters, while small berries

appear at the upper and lower ends of the letters and also at about the centers of the same. Leaves appear to spring upward from 20 the stems or twigs at the upper ends of the letters and also to hang from the twigs at the lower ends of the letters.

What I claim is—

The design for a font of type described and 25 shown.

In testimony whereof I have signed this specification in the presence of two attesting witnesses.

DAVID J. SEAMAN.
